UNITED STATES PATENT OFFICE.

ALBERT C. COUCH, OF BOSTON, MASS., ASSIGNOR, BY MESNE ASSIGNMENTS,
TO THE MICA TIP AND LINING COMPANY, OF SAME PLACE.

HAT OR CAP.

SPECIFICATION forming part of Letters Patent No. 282,441, dated July 31, 1883.

Application filed April 6, 1883. (Model.)

To all whom it may concern:

Be it known that I, ALBERT C. COUCH, of Boston, in the county of Suffolk and State of Massachusetts, have invented certain new and useful Improvements in Hats and Caps, of which the following is a full, clear, and exact description.

This invention consists of a hat, cap, &c., provided with ornamentation, or the name of the manufacture, &c., upon the interior of the hat-crown, covered and protected by a sheet or strip of mica, all substantially as described, reference being had to the accompanying plate of drawings, in which—

15 Figures 1 and 2 are cross-sections of a hat provided with a sheet of mica in accordance with this invention, and Fig. 3 a sectional view in detail.

20 In the drawings, A represents a hat made in any of the usual manners, and of any of the usual or desired styles and shapes, and otherwise, except as to this invention, as ordinary. The inside of the crown B is provided with a suitable design or figure, a, or other character to indicate either the style of the hat, its character, or its manufacture, or for ornamentation or name—as for instance, A. C. Couch, with the ornamentation shown—and over this is secured a layer or sheet, C, of mica, by paste or cement, 25 or any suitable adhesive material, or by stitches, or in any suitable manner, so that said name and ornamentation may be seen, while at the same time it is protected against being soiled, and is rendered glossy in appearance, and the

mica, when soiled, can be readily cleansed 35 without injury to said label and ornamentation. The design or other ornamentation can be printed, &c., directly on the inside of the crown of the hat itself, or on any separate suitable material to be secured to the hat with 40 the mica, as described, and when printed on such separate material it can be secured to the mica sheet in any suitable manner by paste, &c., or by binding the two together by cloth, metal, or any suitable material, as shown at b 45 in Fig. 3, which is a detail cross-section of such, and then the whole secured to the hat in any suitable manner. The mica can be of any size extending beyond the design, if desired.

I am aware that it is old to protect the lining of a hat or cap by a coating of transparent material, and such I do not broadly claim as my invention.

Having thus described my invention, what I claim, and desire to secure by Letters Patent, 55 is—

A hat or cap or other head-covering having the interior of its crown provided with a design or other ornamentation, and a sheet of mica covering and protecting the same, substantially as and for the purpose specified.

In testimony whereof I have hereunto set my hand in the presence of two subscribing witnesses.

ALBERT C. COUCH.
